ATTORNEY

UNITED STATES PATENT OFFICE.

HENRY C. MILLER, OF MILWAUKEE, WISCONSIN.

LOOSE-LEAF-BACKING MEMBER.

1,314,687.

Patented Sept. 2, 1919.

Application filed November 1, 1918. Serial No. 260,674.

To all whom it may concern:

Be it known that I, HENRY C. MILLER, a citizen of the United States, and resident of Milwaukee, in the county of Milwaukee and State of Wisconsin, have invented certain new and useful Improvements in Loose-Leaf-Backing Members; and I do hereby declare that the following is a full, clear, and exact description thereof.

10 My invention relates to new and useful improvements in loose leaf supporting devices, more particularly of that type wherein the series of leaves are slidably mounted on a rod and are confined by a backing member which is slidable to provide finger space between the leaves and to compensate for increasing or diminishing the body of leaves.

15 It is the object of my invention to provide an improved means whereby the backing member may be supported either in an inclined position to provide fingering space between the upper portion of the body of leaves, or may be supported in a vertical position clamping the entire body of leaves.

20 25 A more detailed object resides in the provision of an arrangement whereby the vertical or inclined position of the backing member may be selectively procured by a simple lateral shifting movement of said member.

30 With the above and other objects and advantages in view, which will be apparent as the description proceeds, my invention resides in the novel features of construction, combination and arrangement of parts as hereinafter described and defined by the appended claims.

In the accompanying drawings:

35 Figure 1 is a rear elevational view of a backing member constructed in accordance with my invention, and disposed in clamping position.

40 Fig. 2 is a vertical sectional view on the line 2—2 of Fig. 1.

45 Fig. 3 is a fragmentary rear elevation of the supporting portion of the backing member in inclined or "posting" position.

50 Fig. 4 is a vertical sectional view on the line 4—4 of Fig. 3.

55 Fig. 5 is a side elevational view of a posting cabinet equipped with my improved backing members, and

60 Fig. 6 is a composite view showing in elevation the portions of the backing member

which receive the leaf holding rod of the 55 cabinet.

Referring now more particularly to the accompanying drawings, 5 designates the usual holding rod of a loose leaf retainer which, as shown in Fig. 5 is usually supported on a suitable base member 6 and slightly spaced thereabove whereby to engage in the slots or recesses of a body of loose leaves 7 supported on the base, which base may comprise a slidable drawer or tray. 65

My improved backing member comprises a clamping body plate 8 adapted to engage against one end of the body of leaves on the rod, and provided with a recess 8' receiving the rod 5 and of such width as to permit 70 transverse movement of the plate on the rod. A reinforcing plate 9' of relatively strong and thick metal is secured to the intermediate lower portion of the body plate 8 and is provided with a horizontally elongated slot 10 adjacent its lower end that registers with the upper portion of the recess 9 of the body plate. The lower edge of the reinforcing plate 9 is outwardly directed at 11 to afford a brace rib on the plate. A 75 spring plate 12 is secured at its upper edge to the upper edge portion of the reinforcing plate by rivets 13 passed through all of said plates, and the spring plate extends divergently downward from its point of secure- 80 ment. Adjacent the rod 5, the spring plate is recessed from its bottom edge and said recess is provided at its ends with inward extensions 14 and 15 of differential lengths affording seats for the rod 5, the seat afforded 85 by the recess extension 14 being disposed at a greater elevation than the seat afforded by the recess extension 15, and the intermediate portion of the inner edge of the recess forms a nib between the seats preventing ac- 90 cidental passage of the rod from the lower to the higher seat.

Thus, referring more particularly to Figs. 2 and 4 it is seen that the slot 10 of the reinforcing plate 9 provides a sliding fulcrum 100 for the backing plate whereby said plate may be slid on the rod in accordance with variation with the thickness of the body of leaves held in the device, and whereby the plate may be rocked on the rod to assume a 105 vertical right-angular position with respect to the rod, or may lie at an outward inclination to afford fingering space between the

upper portions of the leaves. The backing plate is held in such vertical position by engagement of the rod 5 in the seat 15, and is held in an inclined position by engagement 5 of the rod 5 in the higher seat 14, and the rod may be selectively disposed in either of these seats by merely swinging the backing plate slightly past its vertical clamping position and then shifting the backing plate 10 transversely of the rod. The spring plate 8 in addition to serving this adjustable supporting function, also efficiently discharges its conventional function of holding the backing plate against movement away from the body of leaves, while at the same time permitting free movement of the body plate theretoward, it being of course understood that the back may be manipulated to permit reverse movement thereof when desired. 15 In Fig. 5, I have shown a portion of a posting cabinet, having one of my improved backing members disposed at each end of the body of leaves. Thus by shifting both of the plates to their inclined position, a maximum finger room is afforded between the leaves whereby the "posting" operation or other manipulation of the leaves may be 20 most conveniently carried out.

What is claimed is:

30 1. A backing member of the class described comprising a body plate adapted for pivotal sliding mounting on a holding rod, and a support member carried by the body plate and having rod seats in differential angular relation to the point of engagement of the body plate with the rod, said seats being selectively engageable with the rod to hold the plate in various angular relations with respect to the rod.

40 2. A backing member of the class described comprising a body plate adapted for pivotal sliding mounting on a holding rod, a spring member carried by said plate, and a plurality of rod seating portions carried by

said spring member to hold the plate in differing angular relations with respect to the rod. 45

3. A backing member of the class described comprising a body plate provided in its lower portion with a transversely elongated opening adapted to loosely receive a holding rod, and a member carried by the backing plate and provided with a plurality of rod seating portions selectively engageable upon transverse movement of the plate, 50 to hold the plate in differing angular relations with respect to the rod.

4. A backing member of the class described comprising a body plate provided with an opening in its lower portion, a reinforcing plate secured to the body plate and covering said opening and provided with a transverse slot in registry with said opening for reception of a holding rod, the lower edge of the reinforcing plate being laterally 60 bent, a support plate secured to the upper portion of the reinforcing plate and divergent therefrom, and a plurality of rod seating portions carried by said support plate to hold the body plate in differing angular relations with respect to the rod. 65

5. A backing member of the class described comprising a body plate provided with an opening in its lower portion adapted to receive a holding rod and permitting 70 transverse movement of the plate on the rod, and a support plate secured to the body plate and having its lower portion spaced from the opening thereof and provided with a rod receiving recess having spaced inward extensions of differential lengths forming seats 75 for the rod.

In testimony that I claim the foregoing I have hereunto set my hand at Milwaukee, in the county of Milwaukee, and State of Wisconsin. 80

HENRY C. MILLER.
